TOY STEERING WHEEL

Jack J. Braude, Los Angeles, Calif., assignor to
Eveo, Inc., Los Angeles, Calif., a corporation
of California

Application March 30, 1948, Serial No. 17,939

5 Claims. (Cl. 46—1)

1

The invention relates to a toy steering wheel, and more particularly to a steering wheel and flexible column therefor, with means, such as a suction cup, for attaching the same to any suitable object such as a toy wagon or the dashboard of an automobile.

The invention particularly relates to improvements in the steering wheel itself and the manner in which it is coupled to the outer end of the flexible column. According to the invention, the steering wheel is provided with a sleeve slightly larger in diameter than the diameter of a round flexible column, the sleeve having spaced from the inside thereof a stud slightly smaller in diameter than the internal diameter of the flexible column. The wheel with its sleeve and stud are molded in one integral piece of thermo-plastic material. To facilitate the draft of the die, the stud is cast concentric with the sleeve, the stud and sleeve being slightly tapered. However this would permit the wheel to drop off from the column. To prevent this, when the casting is taken from the mold and while it is still warm and pliable, the outer end of the stud is pushed to an eccentric position in the outer end of the sleeve, and allowed to cool and harden there so it will pinch the flexible column. This provides a removable coupling which prevents the wheel from falling off while permitting it to be rotated by hand. The advantage of this arrangement is that while the steering wheel, column and suction cup may be taken apart to make a compact package, the coupling between the outer end of the flexible column and the steering wheel is of such a nature that the steering wheel can be readily turned or rotated with reference to the column thereby more nearly simulating an actual steering wheel.

For further details of the invention reference may be made to the drawings wherein

Fig. 1 is a perspective view of the toy steering wheel illustrated as applied to the dashboard of a typical automobile.

Fig. 2 is an enlarged plan view of the front of the toy steering wheel.

Fig. 3 is an enlarged sectional view of the toy steering wheel on line 3—3 of Fig. 2 looking in the direction of the arrows.

Fig. 4 is an enlarged sectional view on line 4—4 of Fig. 2 looking in the direction of the arrows.

Referring in detail to the drawings, the toy steering wheel 1 comprises three elements removably fitting together, namely, the steering wheel 2, the flexible column 3 of rubber or the like and a suction cup 4 of rubber or the like.

The invention relates particularly to the manner in which the steering wheel 2 is coupled to the outer end 5 of the column 3. According to the invention, the column 3 has a round exterior

2

6 and a round bore 7. The steering wheel 2 has three hollow ribs, one of which is indicated at 8 which radiate from a central outwardly facing cup 9. The outer ends of the ribs like 8 merge with the rim 10 of the wheel and preferably the front surface 11 of the ribs is streamlined or tangent with the outer end of the cup 9 as shown at 13 in Fig. 3. Arranged in the cup 9 is a mechanical horn 14 having a push button 15. The bottom of cup 9 has a partition 16 and extending rearwardly therefrom is a sleeve 17 having an internal bore slightly greater than the diameter of the column 3 which may be a piece of hard rubber hose. Coaxial with the sleeve 17 and also rearwardly projecting from the center of the wall 16 is a stud 18 which is preferably the same length as sleeve 17 as shown in Fig. 3, stud 18 being slightly smaller in diameter than the bore 7 of the column 3. After the wheel 2 is taken from the mold and while stud 18 is pliable, its outer end 20 is pushed to an eccentric position and allowed to cool and set there, whereby its portion 21 which is closest to the sleeve 17 provides a gap 22 of less width than the thickness of the column 3. Hence the stud 18 is inclined, its base 24 being concentric with the sleeve 17, while its outer end 20 is eccentric. This makes it possible to force the wheel into position on the column 3, or remove it, and when assembled, the wheel can be turned relatively to the column without the wheel falling off. Preferably a tight frictional grip is provided in the removable coupling 23 between the other end of the column 3 and the cup 4 to prevent the column 3 from turning in the cup 4 when the wheel 2 is operated.

As a result of the above construction, the wheel 2 is readily uncoupled from the outer end 5 of the column 3 and readily coupled thereto while making it possible for the youngster to turn the wheel 2 with respect to the column 3 when assembled thereon. The sleeve 17 and the stud 18 therefore provide a rotatable coupling with the outer end 5 of column 3.

45 It will be apparent that various modifications may be made in the invention without departing from the spirit of the following claims.

I claim:

1. A toy steering wheel of plastic material having a central outwardly facing cup having a bottom wall; a sleeve projecting rearwardly from the rear of said wall; a stud projecting rearwardly from said wall within said sleeve, said stud having a base concentric with and spaced from the inside of said sleeve to provide a gap therebetween, the outer end of said stud having a side surface at a given peripheral region thereof of which is spaced from said sleeve by a smaller gap than the remainder of the periphery at the outer end of said stud to thereby provide a gap

between said sleeve and outer end of said stud at said region which is of less radial width than the gap at the base of said stud; and a resilient, hollow steering column having an end portion fitting inside said sleeve and over said stud, said column having a wall of greater thickness than said smaller gap, whereby to provide a friction grip at said smaller gap for preventing said wheel from falling off said steering column while permitting rotation of said wheel relative to said steering column.

2. A toy steering wheel of plastic material having a central outwardly facing cup having a bottom wall; a sleeve projecting rearwardly from the rear of said wall; and a stud projecting rearwardly from said wall within said sleeve, said stud having a base concentric with and spaced from the inside of said sleeve to provide a gap therebetween, the outer end of said stud having a side surface at a given peripheral region thereof which is spaced from said sleeve by a smaller gap than the remainder of the outer end of said stud to thereby provide a gap at a point between said sleeve and

outer end of said stud which is of less radial width than the gap at the base of said stud.

3. A toy steering wheel comprising, a central outwardly facing cup having a side wall and a bottom wall; a substantially cylindrical sleeve projecting rearwardly from said bottom wall; and a substantially cylindrical stud within said sleeve and also projecting rearwardly from said bottom wall, the inner end of said stud being concentric with respect to said sleeve and the outer end of said stud being eccentric with respect to said sleeve.

4. A toy steering wheel according to claim 1 wherein said stud is round, the interior of said sleeve is round, and said steering column is round and has a round bore, said end portion of said column rotatably fitting in said sleeve and over said stud.

5. A toy steering wheel according to claim 1 wherein said stud is substantially as long as said sleeve.
